UNITED STATES PATENT OFFICE.

JUDSON COOK, OF LEOMINSTER, MASSACHUSETTS.

BRAKE-SHOE.

1,173,700.

Specification of Letters Patent. Patented Feb. 29, 1916.

Application filed January 14, 1916. Serial No. 72,103.

To all whom it may concern:

Be it known that I, JUDSON COOK, a citizen of the United States of America, residing at Leominster, in the county of Worcester and State of Massachusetts, have invented certain new and useful Improvements in Brake-Shoes, of which the following is a specification.

This invention relates to brake shoes of the type wherein a cast-metal body portion is provided with a reinforcing of suitable material, said reinforcing forming the back of the shoe.

The objects of the invention are: to provide a brake shoe with a reinforcing metal back in which the attaching lug is struck up from said reinforcing member; to provide means for firmly holding the reinforcing back in place after the attaching lug has been struck up therefrom; to provide simple and novel means for locking the body of the shoe to the reinforcing back; to provide a simple, cheap and efficient brake shoe of the reinforced type.

With these and such other objects in view as may hereinafter more fully appear, my invention consists in the novel arrangement and construction of parts set forth in the following description, more particularly pointed out in the claims, and which are shown in the accompanying drawing, wherein:

Figure 1 is a central, vertical longitudinal sectional view showing a brake shoe constructed according to my invention. Fig. 2 is a perspective view of the reinforcing back. Fig. 3 is a detail plan view of the connecting plate for the back. Fig. 4 is a plan view of the back as the same appears before the attaching lug has been struck up therefrom.

Referring to said drawing by numerals: The reinforcing back is composed of an elongated plate 1 which is slit near the center to form the tongues 2. The material surrounding the tongues 2 is struck up to form the attaching lug 3, with openings formed therein by the spaces formerly oc-

cupied by the tongues 2, said openings being designated by the numeral 4. A plate 5, 50 provided with a central transverse slit or opening 6, is riveted or otherwise suitably secured to the bottom of the back plate 1 and the ends of tongues 2 are bent to enter the slit 6 and are clamped below the plate 55 5, as shown most clearly at 7, Fig. 1. Near each end of the back 1 two overlapping circular openings 8 are formed or punched for the purpose of allowing the material of the cast body portion of the shoe to enter the 60 same and lock the ends of the shoe firmly to the back. The body portion 9 of the shoe is cast about the back in the usual manner.

Having described my invention, what I claim as new and desire to secure by Letters Patent, is:—

1. A brake shoe having embedded therein a longitudinally extending reinforcing member, the middle portion of said reinforcing member being struck up to form 70 an attaching lug, tongues formed from the attaching lug portion, and means for locking said tongues together.

2. A brake shoe comprising a reinforcing back provided with overlapping circular 75 openings in each end thereof, tongues cut from the back near the center thereof, an attaching lug struck up from the material surrounding said tongues, means for locking said tongues together, and a body portion cast upon the back.

3. A brake shoe comprising a reinforcing back, tongues cut from the back near the center thereof, an attaching lug struck up from the material surrounding the tongues, 85 a plate provided with an opening for the reception of the ends of the tongues secured to the bottom of the back, and a shoe body cast upon the back.

In testimony whereof I hereunto affix my 90 signature in the presence of two witnesses.

JUDSON COOK.
